UNITED STATES PATENT OFFICE.

ALEXANDER T. STEWART, OF PITTSBURG, PENNSYLVANIA.

POTATO-MASHER.

No. 840,392.

Specification of Letters Patent.

Patented Jan. 1, 1907.

Application filed October 3, 1905. Serial No. 281,111.

To all whom it may concern:

Be it known that I, ALEXANDER T. STEWART, a citizen of the United States of America, residing at Pittsburg, in the county of Allegheny and State of Pennsylvania, have invented certain new and useful Improvements in Potato-Mashers, of which the following is a specification, reference being had therein to the accompanying drawings.

10 This invention relates to certain new and useful improvements in potato-mashers; and the invention has for its object to provide a novel form of receptacle into which potatoes or the like vegetables can be placed and 15 crushed by a masher mounted within said receptacle.

Another object of this invention is to provide a potato-masher that can be easily held during the operation of mashing or crushing 20 vegetables contained therein.

Briefly described, my improved potato-masher comprises an inverted-cone-shaped or tapering receptacle the sides of which are perforated. The receptacle is provided with 25 a suitable base and handle, and in said receptacle is mounted a tapering crusher or masher which is adapted to lie in engagement with the sides of said receptacle, said crusher being provided with a revoluble handle, 30 whereby it can be swung around within said receptacle to mash vegetables placed therein and force said vegetables through the perforations of the receptacle.

The above construction will be hereinafter 35 more fully described, and, referring to the drawings accompanying this application, like numerals of reference designate corresponding parts throughout the several views, in which—

40 Figure 1 is a side elevation of my improved potato-masher, and Fig. 2 is a vertical sectional view of the same.

To put my invention into practice, I preferably construct my improved potato- 45 masher of strong and durable metal, which may be plated to give the masher a neat and clean appearance. The potato-masher consists of a receptacle having tapering converging walls which are perforated, as at 2.2.

50 The bottom of the receptacle is formed by an annular base 3, having a central indenture or recess 4, and the side walls are secured to the base, as at 5, whereby a substantially inverted-cone-shaped receptacle will be formed 55 for the reception of potatoes or the like vegetables to be crushed. The walls 1 of the

receptacle, together with the tapering walls of the recess 4, are adapted to aline, as clearly illustrated in Fig. 2 of the drawings. The top edge of the walls 1 of the receptacle is 60 provided with a cap-ring 6, having an annular opening 7 formed therein. The formation of the opening 7 provides an annular flange 8, which is formed at right angles to the sides of the receptacle, the flange 8 overhanging the interior of the receptacle, the object of which will be presently described. 65

The receptacle is provided with a handle 9, which is carried by the cap 6 and the base 3 of the receptacle. In the receptacle is 70 mounted a tapering converging cone-shaped crusher 10, the smaller end of which is adapted to rest in the recess 4 of the base 3, while the upper end is contracted to form a neck portion 11, the contraction of the upper end 75 providing an annular shoulder 12, a portion of which lies beneath the flange 8 when the crusher is resting against the sides of the receptacle. Upon the neck portion 11 of the crusher is revolubly mounted a knob or 80 spherical body 14. This knob is revolubly retained upon the neck 11 by a screw and washer 15.

In operation the smaller end of the crusher 10 is adapted to rest in the recess 4, and when 85 potatoes or the like vegetables are to be mashed within the receptacle the operator moves the masher around within the receptacle, the smaller end of the crusher serving as a pivotal point upon which the crusher is 90 revolved, and as said crusher is carried around within the receptacle the vegetables will be crushed against the perforated sides of the receptacle and forced through said perforations. A person by holding the re- 95 ceptacle by the handle 9 in one hand and gripping the knob 14 with the other can easily operate the crusher within the receptacle and potatoes or the like vegetables can be quickly crushed to a consistency that will 100 be smooth and fine.

It will of course be understood that when potatoes or like vegetables are being crushed the masher is held over a suitable receptacle into which the crushed potatoes or vegetables may fall. 105

It is thought from the foregoing that the construction, operation, and advantages of the herein-described potato-masher will be apparent without further description, and 110 various changes in the form, proportion, and minor details of construction may be re-

sorted to without departing from the spirit of the invention or sacrificing any of the advantages thereof.

What I claim, and desire to secure by Letters Patent, is—

1. A receptacle for mashing potatoes comprising a perforated inverted conical body, a base, a cap-ring overhanging the interior of the body, in combination with a crushing element.
2. The combination in a potato-masher of a receptacle comprising a perforated inverted conical body, and a cap-ring over-

hanging the interior of the body, a tapering crusher of a length and form to fit freely between and find its bearings upon the cap-ring and the inner apex of the cone; and to engage the surface thereof, said crusher having a revoluble handle.

In testimony whereof I affix my signature in the presence of two witnesses.

ALEXANDER T. STEWART.
